UNITED STATES PATENT OFFICE.

CHARLES H. CURTIS, OF EAST SMETHPORT, PENNSYLVANIA.

BULL-ROPE TRIP.

Application filed November 21, 1922. Serial No. 602,471.

This invention is a device for shipping the belt or rope from the bull wheel of a well-digging apparatus, and the object of the invention is to provide a simple and inexpensive device by the use of which the rope or belt may be quickly and easily shipped from the wheel so as to stop the operation of the apparatus without liability of any of the parts being broken. The invention is 10 illustrated in the accompanying drawing and will be hereinafter fully set forth.

In the drawing:

Figure 1 is a plan view of my shipper showing it in operative relation to a bull 15 wheel;

Fig. 2 is a perspective view of the shipper, and

Fig. 3 shows a slight modification.

The bull wheel 1 may be of the usual or 20 any preferred construction and the bull rope 2 is trained around the same in the usual manner. Adjacent the bull wheel, I provide a supporting frame consisting of a strap or bar 3 having its ends downturned, as at 4, 25 to constitute supporting legs and having the lower terminals of said legs spread outwardly to form feet 5. Encircling the legs 4 is a rim or ring 6 which is provided with notches in its lower edge at diametrically opposite points to fit over the feet 5 whereby 30 the lower edge of the said ring may rest upon the ground or the platform. At diametrically opposite points, between the said notches, the ring is provided with lugs or 35 feet 7 through which fastening devices may be driven into the ground or the platform upon which the apparatus is mounted, it being understood that the feet 5 are secured in place in the same manner. The height 40 of the ring is somewhat less than the height of the legs 4 so that the cross bar or metallic strap 3 will be disposed in a plane slightly above the upper edge of the ring. Resting on the upper edge of the ring and passing 45 under the bar is a shipping lever 8 which may conveniently be a flat bar, as shown, and this lever is provided near one end with a plurality of openings 9 through any one of which and the center of the bar 3, a pivot

50 pin 10 may be inserted. The shipping lever is provided at one end with an upstanding pin or roller 11 and at its opposite end is provided with a plurality of openings 12, in any one of which the end of a handle 13 55 may be engaged. This handle 13 may be a rod or pipe of any desired length and is, of

course, to be grasped by the operator when the rope or belt is to be shipped.

When the apparatus is in operation, the shipping lever extends preferably parallel 60 with the bull rope, as shown in Fig. 1, so that the shipping pin or roller 11 will be away from the rope and not apt to accidentally come into contact therewith. When the operation is to cease, a pull is exerted 65 upon the handle 13, thereby swinging the shipping lever about its pivot and carrying the pin or roller 11 into contact with the bull rope, as indicated by dotted lines in Fig. 1, it being understood that the device should 70 be so located that the distance radially of the ring 6 between the center of the ring and the bull rope is less than the distance between the center of the ring and the shipping pin 11. The shipping lever will be 75 firmly supported by the ring but at the same time may move easily thereupon when shipping of the rope is desired, but the lever cannot be swung to such an extent that it will become entangled with the rope or 80 brought into contact with the full wheel inasmuch as the legs 4 constitute stops to limit the shipping movement of the lever, as will be readily understood upon reference to the dotted lines in Fig. 1. The device is 85 exceedingly simple in construction and may be very readily applied to existing apparatus.

While it is desirable to construct the fulcrum bar or strap and the base ring or rim 90 as separate elements, they may form one integral structure, and in Fig. 3 are so illustrated. In said form, the fulcrum bar 13 extends diametrically across the base ring 16 and has downturned ends 14 which are 95 integral with the upper edge of the ring and correspond in height to the thickness of the shipping lever. All the feet 17 are integral with the lower end of the base ring.

Having thus described the invention, what 100 is claimed as new is:

1. In a bull rope trip, the combination of a ring having means whereby it may be secured to a fixed support, a supporting bar extending diametrically across the said ring and having legs fitting within the ring and against the same and provided at the lower ends of the legs with feet extending through the ring and adapted to be secured to a fixed support, and a shipping lever extending 105 across the ring and under the said bar and pivoted to the bar concentric with the ring. 110

2. In a bull rope trip, the combination of a ring having means whereby it may be secured to a fixed base, a bar extending diametrically across said ring, said bar having legs fitting within the ring and provided at their lower ends with feet extending through corresponding notches in the ring and adapted to be secured to the fixed base, and a

shipping lever resting upon and extending across the ring under said bar and adjustably pivoted to the bar concentric with the rings, said legs forming stops for limiting the tripping movement of said lever. 10

In testimony whereof I affix my signature.

CHARLES H. CURTIS. [I. s.]
